UNITED STATES PATENT OFFICE.

LAURENCE M. OAKLEY, OF TRENTON, NEW JERSEY.

DESIGN FOR A COMBINED SHOE SOLE AND HEEL.

Application filed September 11, 1925. Serial No. 14,753. Term of patent 3½ years.

To all whom it may concern:

Be it known that I, LAURENCE M. OAKLEY, a citizen of the United States, residing at Trenton, in the county of Mercer and State of New Jersey, have invented a new, original, and ornamental Design for Combined Shoe Sole and Heel, of which the following is a specification, reference being had to the accompanying drawing, forming part thereof.

Figure 1 is a bottom plan view of a complete sole and heel embodying the invention;

Figure 2 is a cross-sectional view of the same taken on the line 2—2 of Figure 1.

I claim:

The ornamental design for a combined shoe sole and heel as shown.

LAURENCE M. OAKLEY.
